Albert G. Powers, of Lansingburgh, N. Y.

Administrator of Antoine Glomenski, deceased.

Whole No. 1505.

Letters Patent No. 140, dated Decr. 3, 1861.

The schedule referred to in these Letters Patent and making part of the same.

To all whom it may concern:

Be it known that Antoine Glomenski, late of the town of Lansingburgh, County of Rensselaer and State of New York, now deceased, having in his life time invented and produced a new and original design, for printing or stamping upon Floor Oil Cloths, or other fabrics, the subscriber his administrator and legal representative does hereby declare, that the following is a full and exact description of the same, reference being had to the drawings accompanying this specification, viz:

The pattern consists in general of two octagons in slightly unequal size, one of which is of light ground surrounded by bands of white, and having upon its centre an ornamental cross.

The other octagon has the ground made up of parallel lines of differing tints of color, the ground being surrounded by lines or bands of darker color than itself.

These octagons are so disposed in repeating the pattern that the parallel lines in the adjoining darker ones run in contrary directions. The two octagons are separated from each other by black or narrow lines and chevrons, the latter being broken by a line of lighter color a short distance within their outer edges.

The whole design and arrangement being shown upon the accompanying drawings.

And what is claimed as the invention of the said deceased Antoine Glomenski, and desired to be secured by Letters Patent, is the design or pattern described in the foregoing specification and the drawings accompanying the same.
